UNITED STATES PATENT OFFICE

FRITZ DIEBOLD, OF ZURICH, SWITZERLAND, AND OSCAR FRIEDEBERG, OF BERLIN, GERMANY

COMPOSITION FOR CLEANING GLASS WINDOWS

No Drawing. Application filed October 16, 1926, Serial No. 142,146, and in Germany April 29, 1925.

The present invention refers to a process for cleaning glass windows and such like (ceramic surfaces), a composition for carrying out this process and a method for making the said composition.

The object of the invention is to avoid the expensive leather pieces hitherto necessary for cleaning windows and economize work. The composition of matter has the effect to separate as water soluble as fat soluble substances from the glass or the other surfaces and has the property to be removed from the glass by means of pieces of any material.

The process consists in washing the window surface with a composition consisting of a liquid hydrocarbon, suitable for dissolving fatty substances, emulsified with an aqueous colloidal liquid, removing the liquid from the window and rubbing the window with an absorbing web as for instance textile material, paper also printed.

The composition of matter consists of a liquid hydrocarbon and an aqueous colloidal liquid emulsified with each other. The composition forms a disperse system of fats dissolving liquids and aqueous liquids dissolving the dirty parts soluble in water. The hydrocarbon and the aqueous liquid do not mix with each other to an homogeneous mixture, but must produce by suitable treatment an emulsion, in which disperse system the particles are so small that the adsorbing power of the surfaces appears. These small particles are able to adsorb the dirt substances.

Suitable hydrocarbons are: petroleum, petrol oils, gasoline, benzene (pure or commercial). As aqueous liquid solutions of soaps are used (potassium or sodium soap of solid or liquid fatty or resin acids or mixtures of them).

A suitable mixture consists of an emulsion of 70 parts by weight of hydrocarbons emulsified in 30 parts by weight of a 5 per cent solution of sodium soap. Instead of soaps one may use other colloids.

A suitable process for making the composition consists in causing a mixture of petrol oils with fatty acids to flow under agitation in a solution of alkaline hydroxides or carbonates, preferably equivalent to the amount of

the fatty acids. One agitates while adding the hydrocarbon mixture with the fatty acids to the alkaline solution neutralizing the fatty acids and forming from them an aqueous solution of soap. One may also mix under agitation petrol oils with a saponaceous solution.

In order to avoid or diminish a separation of the mixture during storing it is suitable to add the fat dissolving substance another liquid apt for homogeneously being mixed with it, having a higher specific gravity than the fat dissolving liquid in such amount that the specific gravity of the fat dissolving substance is about the same of the aqueous liquid. Such liquids are for instance halogenated hydrocarbons, carbon tetrachloride or others. The preparation of the mixture can be carried as follows:

A mixture of 100 parts by volume of petrol oils and 33 parts by volume of carbon tetrachloride is poured under agitation into an aqueous saponaceous solution containing 5 percent soap.

We claim:—

1. A composition of matter for cleaning shining surfaces comprising a thin liquid vehicle consisting of a dilute alkaline soap solution, and gasoline dispersed throughout said vehicle as fine particles capable of remaining stably suspended and capable of adsorbing dirt or the like from soiled surfaces.

2. A composition of matter for cleaning shining surfaces comprising a thin liquid vehicle consisting of a dilute alkaline soap solution, and a mixture of gasoline and carbon tetrachloride dispersed throughout said vehicle as fine particles capable of remaining stably suspended and capable of adsorbing dirt or the like from soiled surfaces.

In testimony whereof we hereunto affix our signatures.

FRITZ DIEBOLD.
OSCAR FRIEDEBERG.
